BUILDING CONSTRUCTION

Nathan Davidson, Los Angeles, Calif.

Application September 23, 1935, Serial No. 41,749

4 Claims. (Cl. 72—30)

My invention relates broadly to building construction and more particularly to a novel type of brick for use in said construction which makes possible a simple and effective reenforced wall that will withstand various types of strain and shocks, particularly those arising from earthquakes and like disturbances.

Brick construction has long been recognized as an economical and desirable means for building, but heretofore it has had one inherent weakness in that the bricks used and the conventional method of forming the brick construction have failed to produce structures which can withstand severe earthquakes. It is therefore the principal object of my invention to provide a brick which is both simple and durable and which lends itself to the building of a structure which is highly resistant to earthquakes and like shocks. I accomplish this in general by providing a brick having grooves in one of its vertical faces.

It is also an object of my invention to provide a brick which can be adjustably tied in to other bricks to give additional strength to the structure wherein they are used, so that a wall comprising two or more tiers of bricks made according to my invention can be formed with bricks of slightly varying dimensions and still be both highly resistant to earthquakes and symmetrical.

It is a further object of my invention to provide a system of combining reenforcing steel with a brick structure in such a manner that the structure will have a series of steel cored vertical locks or keys which add greatly to the strength of a wall made with my novel type of brick.

For the purpose of defining the term "brick" as used throughout the specification and claims, I adopt the following definition found in the Clay Products Manual, published by the Clay Products Institute of California, and it is to be understood that wherever I use the term brick, I mean a structural unit made from clay or shale formed while plastic into the desired shape and size, usually rectangular and then burned at a high temperature in a kiln, usually about 2000° F.

These and other objects of my invention will become readily apparent from the following description of a preferred form thereof and from the accompanying drawing in which:

Fig. I is a perspective of a section of wall built according to my invention.

Fig. II is a perspective of my preferred form of brick.

Fig. III is a plan section of a two course wall taken at 3—3 in Fig. I.

Fig. IV is a side elevation of the horizontal tie rod.

Referring now to the drawing, and particularly to Fig. II thereof, the numeral 10 indicates generally a brick of substantially conventional length and breadth, but preferably of more than conventional depth, although the exact dimensions and proportions may be varied at will depending on the need. The ends 11 and 12, and the side 13 are formed as plain rectangular surfaces, the brick 10 preferably being a rectangular parallelepiped in over-all shape. The side or vertical face 14 is provided with a plurality of (preferably 3) substantially vertical semi-cylindrical grooves 16, 17 and 18, equally spaced along the face 14 and substantially parallel to each other. A pair of vertical holes 19 and 20 extend through the brick approximately midway between the faces 13 and 14, although if desired they need not go clear through the brick. The shape of that portion of the internal face of holes 19 and 20 adjacent to the face 13 is immaterial, but can conveniently be made semi-cylindrical for ease of construction. The internal hole face adjacent the brick face 14 may be formed as a semi-cylindrical surface with a projecting shoulder 21 therein to provide a pair of walled recesses 25 and 26 differentially spaced from the brick face 14 to provide inner and outer bearing surfaces for the horizontal ties hereafter described.

Referring now to Fig. III wherein a section of wall is shown, the bricks being designated as 10, 10a, 10b, 10c and 10d, it will be noted that the bricks are laid with their grooved faces 14 opposing each other and with the end groove 16 of brick 10 being immediately opposite end groove 18a of the opposing brick 10a. The middle groove 17 of brick 10 is opposite the junction of the bricks 10a and 10b and end groove 18 of brick 10 is immediately opposite end groove 16b of brick 10b. Staggering the bricks thusly is of course in accord with conventional bricklaying practice. However, by providing the grooves 16, 17 and 18, and the corresponding grooves in the other bricks, a solid vertical key is formed binding the bricks against longitudinal shock when grout or other cementitious material is poured between the bricks to fill the respective grooves and form a solid hard body therein.

As additional means of strengthening the wall against lateral movement of the bricks, ties 23 may be provided in the form of simple wire hooks laid horizontally across the bricks with depending ends 27 and 28 insertable into the oppositely positioned holes 19 and 20 of opposing bricks. It

is of course essential that the outer faces of the bricks be in one plane so that the wall will be relatively even and smooth. It is well known that bricks will vary in size due to numerous causes and this is particularly true in the case of hard burned bricks which because they have a higher shrinkage on burning are more apt to vary in resulting size. To take care of this factor the holes 19 and 20 are formed with a plurality of recessed faces at different distances from the brick face 14 as previously described so that although all of the ties 23 are of the same length, the individual brick positions can be varied to allow for differences in size.

15 As will be seen best from Fig. III a number of positions of adjustment are possible for the ties 23 when used in combination with holes 19 and 20 of the type previously described, making it possible to adjust the lateral position of the bricks 20 with respect to each other and the outside face of the wall to compensate for slight variations in size of the bricks due to any uneven molding, firing or other causes.

In Fig. III proceeding from left to right, it 25 will be seen that the tie 23 runs from the inner recess of hole 19a to the outer recess of hole 20c. The tie 23a runs from the outer recess of hole 20a to the inner recess of hole 19. The tie 23b runs from the inner recess of hole 19b to the 30 outer recess of hole 20 and the tie 23c runs from the inner recess of hole 20b to the inner recess of hole 19d. The tie 23d runs from the outer recess of hole 19e to the outer recess of hole 20d.

As previously mentioned, by pouring a cementitious grout between the bricks to fill up 35 the cavities formed by the vertical grooves, a series of vertical pillars or locks is formed between the two courses of brick which because of they completely fill the grooves and because of 40 the bond between grout and the brick face effectively prevent any longitudinal movement of the bricks of one course with respect to those of the other, this being particularly true when horizontal ties such as those illustrated at 23 are 45 used to hold the bricks against lateral motion. In practice the holes 19 and 20 after the ties 23 are placed may either be filled with mortar or may be filled with grout depending on the strength desired.

50 Referring now to Fig. I wherein is portrayed a section of wall built according to the foregoing description, it will be seen that I have illustrated a system of reenforcing steel in combination with the grooved bricks previously described. By placing vertical steel rods between the courses and immediately opposite one or more vertical 55 grooves, additional rigidity and strength is given to the structure. A cementitious grout is poured between the bricks as before and consequently 60 surrounds the vertical steel reenforcing rods so that the vertical pillars or locks thus formed are steel cored to give additional strength against horizontal movement. If desired, horizontal reenforcing rods 30 may also be employed at appropriate intervals, these preferably being laid 65 across the horizontal ties 23 to hold the same in position prior to the pouring of the grout.

70 While I have shown the vertical grooves as being semi-cylindrical, it will be understood of course, that other shapes would also be applicable. Likewise while I have illustrated a brick employing three grooves as my preferred form and best adapted for ordinary brick work, it will be evident that the brick could be provided with

a varying number of grooves, depending on the size and material of the brick and the type of construction in which it is used.

The holes 19 and 20 as illustrated show a simple means for securing adjustability in positioning the 5 bricks using horizontal ties of a uniform length, but obviously different shaped holes and different shaped recesses may be provided so long as they are differentially spaced from the face 14. I have found from practice that two recesses per hole 10 are sufficient for most brick variations, but if for any reason there is a greater variation in brick size, then additional recesses may be provided to insure the outer faces of all bricks being in one 15 plane.

According to the patent statutes, I have illustrated and described a preferred form of my invention, but it is to be understood that I in no way mean to limit myself to the form shown as the same is merely illustrative of the broad principles 20 involved in my invention as set forth in the appended claims.

I claim as my invention:—

1. A solid building brick of substantially rectangular shape, a series of grooves on one face 25 thereof, and a pair of irregular holes in said brick, one of said holes being opposite the endmost groove at one end of said brick and having its side wall adjacent said groove arranged to provide at least two bearing surfaces at different 30 distances from the bottom of said groove, and the other hole being opposite another groove in said brick and also having the wall thereof adjacent the groove provided with at least two bearing 35 surfaces.

2. A solid building brick of substantially rectangular shape, a series of grooves on one face thereof, and an irregular hole in said brick, said hole being opposite one of said grooves and having 40 its side wall adjacent said groove so formed as to provide at least two bearing surfaces, each being positioned a different distance from the bottom of said groove than the other.

3. A building construction comprising at least 45 two courses of bricks, each brick having vertical grooves in one face thereof and vertical holes therein in horizontal alignment with certain of said grooves, said bricks being laid so that a groove and horizontally aligned hole in each brick of one course lies opposite a groove and horizontally aligned hole in an opposed brick of the 50 adjacent course, and horizontally extending tie rods set in certain of said horizontally aligned holes and extending across the space bounded by the grooves lying in horizontal alignment with 55 said holes.

4. A building construction comprising at least 60 two courses of bricks, each brick having vertical grooves in one face thereof and vertical holes therein in horizontal alignment with certain of said grooves, the wall of each hole adjacent the associated groove being provided with a plurality of bearing surfaces differentially spaced from the associated grooves in said bricks, said bricks being laid so that a groove and horizontally aligned hole 65 in each brick of one course lies opposite a groove and horizontally aligned hole in an opposed brick of the adjacent course, and horizontally extending tie rods set in certain of said horizontally aligned holes and extending across the space 70 bounded by the grooves lying in horizontal alignment with said holes.

NATHAN DAVIDSON.
